(57) **CLAIM**

I claim the ornamental design for a triple head LED solar motion light with camera, as shown and described.

DESCRIPTION

FIG. 1 is a perspective view of a first embodiment of my ornamental design of a triple head LED solar motion light with camera;

FIG. 2 is a left-side elevation view thereof;

FIG. 3 is a front elevation view thereof;

FIG. 4 is a right-side elevation view thereof;

FIG. 5 is a rear elevation view thereof;

FIG. 6 is a top plan view thereof;

FIG. 7 is a bottom plan view thereof;

FIG. 8 is a perspective view of a second embodiment of my ornamental design of a triple head LED solar motion light with camera;

FIG. 9 is a right-side elevation view thereof;

FIG. 10 is a front elevation view thereof;

FIG. 11 is a left-side elevation view thereof;

FIG. 12 is a rear elevation view thereof;

FIG. 13 is a top plan view thereof; and,

FIG. 14 is a bottom plan view thereof.

The broken lines shown in the figures are included for the purpose of illustrating environment and form no part of the claimed design.
